UNITED STATES PATENT OFFICE.

JOHN J. PAULL, OF WELLSBURG, WEST VIRGINIA, ASSIGNOR TO EAGLE MANUFACTURING COMPANY, OF WELLSBURG, WEST VIRGINIA.

DESIGN FOR A FLOWERPOT HOLDER.

Application filed April 9, 1928. Serial No. 26,191. Term of patent 7 years.

To all whom it may concern:

Be it known that I, JOHN J. PAULL, a citizen of the United States, residing at Wellsburg, in the county of Brooke and State of West Virginia, have invented a new, original, and ornamental Design for Flowerpot Holder, of which the following is a specification, reference being had to the accompanying drawing, forming part thereof.

Fig. 1 is a perspective view of the flower pot holder, showing my new design.

Fig. 2 is a side view.

Fig. 3 is a top plan view.

I claim:

The ornamental design for a flowerpot holder, as shown.

JOHN J. PAULL.
